MACHINE FOR PRODUCING DISPLAY CARDS

John Aquilla, Brooklyn, N. Y.

Application December 18, 1946, Serial No. 716,950

7 Claims. (Cl. 154—35)

1

This invention relates to mounts, particularly to paper mounts, and has for its primary object to provide a machine for making display cards for jewelry and the like.

In the jewelry trade it is customary to mount earrings, lockets, etc., upon tissue covered cards to prevent the article of jewelry from tarnishing and also to enhance the appearance of the article as it is displayed. The enhancement of the article also depends upon a certain degree of looseness with which the tissue paper embraces the card. It has been customary heretofore, as far as applicant is aware, to manually loop the tissue paper around the card without securing one directly to the other. Thus in the prior practice the operator first placed one edge of tissue paper adjacent one edge of a cardboard, next continued the paper around the cardboard until it overlapped the first edge, and then applied adhesive, at several points between and adjacent the overlapped edges, leaving an unsecured margin along the last edge of the tissue paper. The combination of cardboard and tissue paper was finally cut according to the size of card required.

While the above practice is, in general, satisfactory, it is necessarily a slow process, being dependent upon the speed of the operator. At the same time, the unsecured margin of tissue paper tends to fray, fold over, and break the adhesive bond, thereby impairing the purpose for which the card was designed. Further, since the tissue paper is not secured to the cardboard, being merely looped therearound it has a tendency to slide off.

It is, therefore, another object of the invention to overcome the above disadvantages by providing a machine that is adapted to affix tissue paper to cardboard along a continuous strip and also to maintain the tissue paper on the cardboard with an optimal degree of looseness.

It is still another object of the invention to provide a machine for mechanically producing display cards, thereby substantially increasing production and lowering the cost thereof.

With the above objects in view, one embodiment of the invention discloses a machine comprising a feeding rack for holding cardboards in an upright position; a plurality of pairs of adhesive applying rollers disposed underneath the rack, so that each cardboard as it passes downwardly therebetween receives adhesive material in strips of predetermined width on both sides thereof; a shelf with an opening underneath the rollers for supporting tissue paper, the cardboard being adapted as it passes downwardly through said

2

opening to engage the tissue paper and fold it against the sides thereof; and a pair of rollers for pressing the tissue paper against the cardboard, whereby one is adhesively secured to the other along the continuous strips, the unsecured intermediate portions of the tissue paper presenting a looseness of predetermined degree. The composite article is then dropped from the compression rollers into a container, after which display cards of appropriate size are cut therefrom by severing the article midway along the adhesive strips and transversely in accordance with the desired length of display card.

A more complete understanding of the invention will be obtained from the following description of a preferred embodiment thereof, taken in conjunction with the accompanying drawings in which:

Fig. 1 shows a vertical sectional view of the machine taken along line 1—1 of Fig. 2;

Fig. 2 is a transverse sectional view taken along line 2—2 of Fig. 1 in which the essential elements of the machine are more clearly illustrated;

Fig. 3 is an enlarged sectional view of a portion of Fig. 2 showing the manner in which the tissue paper is picked up by the cardboard and secured thereto.

Fig. 4 is a perspective view of the completed composite article after having been acted upon by the apparatus of Figs. 1 and 2, the adhesive strips for securing the tissue paper to the cardboard being outlined in dotted lines; and

Fig. 5 is a perspective view of a display card cut out of the composite article shown in Fig. 4.

Referring now to the drawings, particularly to Figs. 1, 2 and 3, there is shown a pair of uprights 10 having at the upper portion thereof a hopper or feeder rack 12 for carrying a supply of cardboards 14 in a more or less upright position. The feeder rack 12 may be of any suitable construction and, in the embodiment shown, preferably comprises a base member 16 having a slot 18 therein for passage therethrough of individual cardboards 14; a pair of sides 20 that are adjustably mounted on the uprights 10 by the usual thumb screw and nut combination 22 in which plate elements 24 at the ends thereof are rigidly secured to the sides 20; and rods 26, 28 constituting the back and front elements, respectively, thereof. As seen in Fig. 2, the front rods 28 are disposed just in front of the slot 18 to act as a stop, so that, as each cardboard 14 reaches the slot, it will automatically drop therethrough. To further insure this registration, the front of the base 16 is shown made of thicker material, al-

though the base 16 may be of uniform thickness throughout with a backstop mounted adjacent the slot 18.

Underneath the feeder rack 12 is disposed an adhesive applicator 29 constituting a pair of shafts 30 suitably journaled in the uprights 10 with a plurality of paired rollers 32 fixedly secured and longitudinally spaced at appropriate intervals. Each roller 32 is of predetermined width and is provided on its external periphery with a resilient material 34, preferably of rubber. The spacing between the pairs of rollers 32 may be varied in any of a number of ways, such as by means of a set screw 33 mounted in the hub thereof and adapted to engage the peripheral surface of the shaft 30.

The shafts 30 and, in turn, the rollers 32 are disposed a predetermined distance apart, so as to leave a space therebetween sufficient to permit the cardboard 14 to pass therethrough. Such space is preferably less than the thickness of the cardboard in order to permit a gripping effect by the rollers thereupon, whereby the cardboard will be driven downwardly, as viewed in Fig. 2. Each roller 32 is in contact engagement with a roller 36, which is fixedly disposed upon a shaft 38, the rollers 36 being adapted to apply adhesive mixture 39 from a container 40 to the rollers 32. The container 40 may be of any suitable configuration and is shown supported upon bars 42 affixed to the uprights 10 in any suitable manner. As seen in Fig. 1, there are four pairs of rollers 32 and 36 provided and these rollers are adapted to apply the adhesive mixture 39 to both sides of the cardboard 14. The mixture 39 may comprise any suitable quality of adhesiveness, such as glue and the like, but it is preferable to use what is known as a white padding cement in order to prevent discoloration of the cardboard 14.

Below the adhesive applicator 29 is shown a shelf 44 having a slot 46 midway between the right and left extremities thereof, as viewed in Fig. 2, the sides of the shelf 44 being rigidly secured to the uprights 10. The shelf 44 is provided as a supporting element for a sheet of tissue paper 47 that is to be applied to the cardboard 14 in a manner to be described hereinafter.

Directly under the shelf 44 is shown a pair of rollers 48 and 50, preferably of steel, mounted upon shafts 52 and 53, respectively, that are suitably journaled in the uprights 10. Roller 48 is rotatable about a fixed axis, while roller 50 is rotatable about a variable horizontal axis being urged against roller 48 by a resilient compression spring member 54 adjacent the ends thereof, which spring is secured at one end to the upright 10 and connected at the other end to a slideable element 56 disposed upon the shaft 52. It is thus seen that the rollers 48, 50 function as compression rollers and are adapted to press the cardboard and tissue paper together.

To maintain the cardboard 14 in vertical alignment during its passage through the device and also to enable the device to accommodate a plurality of sizes of cardboards, a pair of aligning rods 58 are disposed below the slot 18, while a second pair of rods 60 are interposed between the adhesive applicator 29 and the shelf 44. The rods 58 and 60 are each spaced a predetermined distance apart, so as to permit the cardboard to freely pass therebetween, as will become more apparent upon investigation of Figs. 2 and 3. Referring to these two figures, it will be noted that the slot 18, the respective spaces between

the rollers 32, rods 60, and the slot 46, and the contact point between the compression rollers 48, 50 are in vertical alignment. It is, of course, understood that the rods 58 and 60 may be dispensed with in the event that cardboards of sufficient length are utilized. In other words, if the cardboard 14 is of such length that one end of it is adapted to lie within slot 18 while the other end thereof is positioned in slot 46 of shelf 44, there is no need for any other alignment means. Further, to prevent the alignment rods 60 from removing some of the cement 39 from the cardboard during its passage therebetween, it is preferable to undercut these rods at the portions 62 indicated in Fig. 1.

The power supply for driving the device may be of any suitable type, such as an electric motor (not shown) coupled through a suitable reduction gear train (not shown) to a gear 64 fixedly secured to one end of shaft 53. The other end of shaft 53 is shown provided with a sprocket 66, which is coupled by means of a chain 68 to a sprocket 70 fixedly mounted upon one of the shafts 30. Also fixedly secured to this shaft 30 and rotatable with sprocket 70 is a gear 72, which is in mesh engagement with a second gear 74 fixedly mounted upon the other shaft 30. Similarly, a pair of meshed gears 76, 77 are respectively mounted on the shafts 52 and 53, gear 76 rotating with sprocket 66 and driving gear 77. From the above it is apparent that the gears 72, 74, 76 and 77 rotate concurrently and are driven by gear 64.

In operation, the cardboards 14, which are stacked in a substantially upright position in the rack 12, are moved transversely toward the slot 18 after which each cardboard 14 drops through said slot between the rods 58 (when provided), thence between rollers 32, whereupon the cement 39 is applied thereby to both sides of the cardboard in adhesive strips 78 of predetermined width. The rollers 32 drive the cardboard 14 downwardly to a position between rods 60 and, as the cardboard approaches slot 46 in shelf 44, it first engages the tissue paper 47 resting thereupon and then, while it is passing through the slot, folds the same along both sides thereof. (See Fig. 3.)

The folded tissue paper 47 and cardboard 14 next pass through the compression rollers 48 and 50, which seal the combination into a laminated or composite article 80, the tissue paper being adhesively secured to the cardboard only along the adhesive strips 78, shown in dotted outlines in Fig. 4.

It is to be noted that the tissue paper 47 is not secured to the cardboard between the intervals 78 and is thereby provided with a certain amount of looseness which adds to the attractiveness of the completed article. After passing through the compression rollers 48 and 50, the composite article 80 is then dropped into a receptacle (not shown). At a later step of manufacture the composite article 80 is severed into individual display cards 82, shown in Fig. 5. This is accomplished by cutting longitudinally the composite article 80 midway along the adhesive strips 78 and transversely across the article in accordance with the length of display card 82 desired.

While this invention has been shown and described with reference to certain particular embodiments merely for the purpose of illustration, it is understood, of course, that various modifications may be made in the details of construction of the machine without departing from the scope

of this invention, as defined in the appended claims.

What I claim is:

1. A machine for making a composite article comprising, in combination, a plurality of pairs of revolvable members for applying adhesive material at spaced intervals to a cardboard as it passes therebetween, a shelf having an opening underneath said members for carrying a sheet of tissue paper, said revolvable member being arranged to drive said cardboard through said opening, whereby said tissue paper is folded along the sides of the cardboard as it passes through said opening, and a pair of revolvable elements for compressing and sealing at said intervals said tissue paper and cardboard into said composite article.

2. A laminating machine comprising, in combination, a plurality of pairs of rollers for applying cement at spaced intervals to both sides of a cardboard, a shelf having a slot underneath said rollers for carrying a sheet of tissue paper, said slot being substantially at the midpoint of said tissue paper, said rollers being adapted to drive said cardboard through said slot, whereby said tissue paper is folded along the sides of said cardboard, and another pair of rollers for seizing said cardboard and folded tissue paper and compressing them into a composite article, said last mentioned pair of rollers being further adapted to eject the composite article from the machine.

3. A machine for making a composite article comprising, in combination, means for supporting a cardboard in an upright position, a plurality of pairs of rollers disposed underneath said means for applying adhesive material at spaced intervals to said cardboard, a shelf having an opening for carrying a sheet of tissue paper, said rollers being arranged to drive said cardboard through said opening, whereby said tissue paper is folded along the sides of said cardboard as it passes through said opening, and a pair of compression rollers disposed underneath said last opening, said compression rollers being adapted to press said tissue paper in adhesive engagement at said intervals with said cardboard.

4. A machine for affixing tissue paper to a cardboard comprising, in combination, a rack for supporting a plurality of cardboards, said rack having an opening in the bottom thereof through which one of said cardboards is adapted to pass; a plurality of pairs of rollers disposed underneath said rack for applying strips of adhesive material at spaced intervals to said cardboard, a shelf having an opening in alignment with said first opening for carrying a sheet of tissue paper disposed below said rollers, said rollers being arranged to drive said cardboard through said opening, whereby said tissue paper is folded along the sides of said cardboard, and a pair of compression rollers disposed underneath said last opening, said compression rollers being adapted to press said tissue paper in adhesive engagement at said intervals with said cardboard and to eject them from the machine.

5. A machine comprising, in combination, means for supporting a plurality of cardboards, means for maintaining each of said cardboards in an upright position as it passes through said machine, a driving means, a plurality of spaced

pairs of rollers driven by said power source for applying spaced adhesive stripes to both sides of said cardhoard, a shelf having a slot for carrying a sheet of tissue paper, said paper being disposed over said opening and underneath said rollers, and a pair of compression rollers disposed underneath said slot and driven by said power source, said first mentioned rollers being arranged to drive said cardboard through said slot, whereby said tissue paper is folded along the sides of said cardboard, and said compression rollers being adapted to press said tissue paper in adhesive engagement at said strips with said cardboard to form a laminated article.

6. A machine comprising in combination, a rack for supporting a plurality of cardboards, said rack having an opening in the bottom thereof through which one of said cardboards is adapted to pass; a pair of horizontal rods disposed underneath said opening, said rods being spaced apart a predetermined distance with the open space therebetween directly below said rack opening for maintaining each of said cardboards in an upright position, a plurality of pairs of adjustable rollers disposed in spaced relationship underneath said rods for applying adhesive material in spaced strips to both sides of said cardboard, a second pair of spaced rods having undercut portions in alignment with and disposed underneath said rollers, a shelf having an opening for supporting a sheet of tissue paper, said opening being in alignment with said previous spaced openings, and a pair of compression rollers disposed underneath said last opening, said adjustable rollers being arranged to drive said cardboard through said last opening, whereby said tissue paper is folded along the sides of said cardboard, and said compression rollers being adapted to press said tissue paper in adhesive engagement at said strips with said cardboard.

7. A machine for affixing tissue paper to a cardboard comprising, in combination, a rack for supporting a plurality of cardboards, a shelf having an opening disposed below said rack for carrying a sheet of said tissue paper, means including a plurality of paired rollers for applying adhesive material of predetermined widths at spaced intervals to said cardboard, said means being disposed intermediate said rack and said shelf, said rollers being arranged to drive said cardboard through said opening, whereby said tissue paper is folded along the sides of said cardboard, as it passes through said opening, and means including a pair of rollers for pressing said tissue paper against said cardboard and sealing said paper and cardboard together at said spaced intervals.
